UNITED STATES PATENT OFFICE.

CHARLES L. PEIRCE, JR., OF CHICAGO, ILLINOIS, ASSIGNOR TO THE W. G. NAGEL ELECTRIC COMPANY, OF TOLEDO, OHIO, A CORPORATION OF OHIO.

CABLE-HANGER.

941,039.

Specification of Letters Patent. Patented Nov. 23, 1909.

Application filed September 13, 1906. Serial No. 334,381.

To all whom it may concern:

Be it known that I, CHARLES L. PEIRCE, Jr., a citizen of the United States, and a resident of Chicago, in the county of Cook 5 and State of Illinois, have invented a certain new and useful Improved Cable-Hanger; and I do hereby declare the following to be a full, clear, and exact description of the invention, such as will enable others skilled in the art to which it appertains to 10 make and use the same, reference being had to the accompanying drawings, and to the figures of reference marked thereon, which form a part of this specification.

15 My invention relates to improved means for suspending electrical conductor-cables or the like from their supporting or messenger-wires, and the object of the invention is to provide a device of this character, the clip 20 or messenger-engaging member of which is stamped from sheet-metal and shaped to form a simple, durable and efficient means to which the suspender member may be easily and quickly secured without liability 25 of accidental displacement.

A further object of my invention is to provide a hanger which combines a maximum amount of strength with a minimum amount of material, whereby to cheapen its 30 construction without depreciating its practicability or commercial value.

The invention is fully described in the following specification and illustrated in the accompanying drawings, in which,—

35 Figure 1 is a perspective view of my improved hanger applied to a conductor cable and its messenger-wire. Figs. 2 and 3 are different elevations of the clip or messenger-engaging member of the hanger, and Figs. 40 4 and 5 are plan and side views, respectively, 45 of the clip blank.

Referring to the drawings, 1 designates the portion of my improved hanger which forms the clip or hook and rides on or engages the 45 messenger-wire 2, and 3 the portion thereof, which forms the suspender or loop member for engaging with and supporting the conductor-cable 4.

The clip or hook 1 comprising the features 50 of my present invention is stamped from sheet-metal and formed in inverted U-shape to adapt it to straddle and ride on the messenger-wire 2. The blank 5 from which the clip is formed has its ends slotted for a suitable distance longitudinally thereof, as

shown at 6, to form the spaced companion tongues 7 on each end thereof. These tongues are bent outwardly and upwardly to form companion hooks on each terminal of the clip, and are spaced sufficiently apart by 60 the provision of the slot 6 to permit an easy insertion of the co-operating end of the loop member 3 therein, as shown in Fig. 1. The ends of these tongues are drawn closer to the body of the clip than their base portions, so 65 as to require the application of force to the end of the suspender or loop member 3 to discharge it therefrom, thus preventing accidental displacement. The body or messenger-engaging portion of the clip or hook 70 1 is preferably pressed oval in cross-section so as to present a rounded surface to the messenger.

The suspender or loop member 3 preferably used in connection with this construction of hook consists of a cord, wire or other flexible member of sufficient length to enable it to be looped around the conductor-cable and having its ends knotted or provided with enlargements 8 to prevent them from 80 being pulled through the intervening openings between the hooked tongues 7 when under strain. It is preferable to depress the inner edges of the tongues at their loops or base portions, as shown at 9, to provide a 85 concaved seat for the enlargements 8 of the suspender so as to lessen the danger of their being cut by contact with the sharp edges of the tongues.

Having thus described my invention, what 90 I claim as new, and desire to secure by Letters Patent, is,—

A cable-hanger comprising a messenger straddling member and a pliant suspender, the messenger straddling member being 95 stamped from a flat sheet and bent upon itself to form an inverted U-shaped member and having its ends each bifurcated and the forks thus formed bent up contiguous to the depending legs of the member to form 100 co-operating securing means for the ends of the suspender.

In testimony whereof I have hereunto signed my name to this specification in the presence of two subscribing witnesses.

CHARLES L. PEIRCE, JR.
